UNITED STATES PATENT OFFICE

2,592,163

AUDIBLE RAILROAD CROSSING WARNING SIGNAL

Sydney W. Madden, Chicago, Ill.

Application September 7, 1949, Serial No. 114,346

1 Claim. (Cl. 246—125)

1

My invention relates to audible railroad crossing signals. Most railroad crossing signals in present use are of the bell ringing type, which have such a common sound as often to be ignored by motorists and pedestrians at railroad crossings, as well as often being confused with bell signals for other purposes. Therefore, it is a prime object of my invention to provide an audible railroad crossing warning signal in which the sound of the onrushing train is picked up, amplified and audibly transmitted by loud speakers placed at railroad crossings, bringing a loud and realistic sound of the speeding railroad train, which would attract the attention of motorists and pedestrians at the said railroad crossings, causing them to stop and thereby avoiding many railroad crossing accidents.

A further important object of my invention is to provide an audible railroad crossing warning signal wherein the sound of the rushing train vibrated through the rails is picked up by microphones spaced at intervals and clamped to the said rails, to be carried to loud speakers placed at the railroad crossings.

A still further object of my invention is to provide an audible railroad crossing warning signal, having signal pick-up microphones attached or clamped in series to one of the rails of the railroad track on both sides of the crossing for a sufficient distance to give ample warning of the oncoming train at the railroad crossing.

A further object of my invention is to provide an audible railroad crossing warning signal that is of simple design and construction and may be economically produced in quantity and quickly and easily installed.

Other objects and advantages embraced in my invention will be disclosed in the following description and the accompanying illustrations, wherein like parts are designated by like numerals and in which:

Fig. 1 is a plan view of two parallel railroad tracks with a road intersection or crossing and showing the spacing of the rail attached microphones and their connections to loud speakers located one facing each way at the railroad crossing; electrical wiring having been omitted for clarity.

Fig. 2 is an enlarged cross section of one of the rails of the railroad, showing the clamping attachment thereto of one of the microphone assemblies and its electrical connections.

Fig. 3 is a side view of the clamp attached microphone and a portion of the rail taken looking in the direction of arrows 3—3 on Fig. 2.

2

Fig. 4 is a view of the loud speaker assembly mounted on a loud speaker supporting pole.

Fig. 5 is a view, partly in cross section, of the loud speaker assembly, taken substantially on line 5—5 on Fig. 4.

Fig. 6 is a schematic wiring diagram of the electrical connections between the microphone pick-up units, the amplifier and the loud speaker.

Referring to the illustrations, my invention is generally designated 7 and consists of a microphone assembly 8, and a loud speaker assembly 9, inter-connected by an insulated cable 18. The said microphone assembly 8 consists of a microphone 10, within a waterproof microphone casing 11, having a rubber sealing washer 37 about its mouth which is maintained in contact with the web portion 14 of a rail 15 between two of the ties 35 and held securely in place by a clamp 12. The said clamp 12 has a microphone attaching portion 34 to hold microphone 8 against the web 14 of rail 15, and a clamp tightening screw 13 as illustrated in Figs. 2 and 3. A microphone ground wire 16 connects the microphone to clamp 12 and a cable connecting wire 17 would preferably run through a pipe or lead casing underground to the nearest telephone or telegraph post 36, which it would connect to the insulated cable 18. The said cable 18 would preferably be suspended along the telegraph posts which ordinarily run parallel to the railroad right-of-way and would be connected to amplifier connecting wire 19.

The loud speaker assemblies 9 consists of amplifiers 20 and loud speakers 23, mounted upon loud speaker supporting poles 25. The said supporting poles 25 would preferably be located one on either side of the railroad track or tracks, facing the direction of oncoming traffic at the railroad crossing. Amplifier ground wires 21 connect to rail 15 to complete the circuit between the amplifier 20 and microphone 10. Loud speaker wires 22 connect amplifier 20 to loud speaker 23 and amplifier power wires 24 providing electrical power to the said amplifier 23, are connected to any convenient source of electrical power.

Since most railroad trains are at least a quarter of a mile in length, therefore, the microphone units 8 would preferably be attached to the railroad tracks at quarter-mile intervals for a distance of about one and one-half miles either side of the railroad crossing 29. This would enable the warning sound from a train going as fast as one hundred miles an hour to be picked up by loud speakers 23 in sufficient time to permit

the vehicles designated 30 in Fig. 1, or pedestrians to stop even before the train is visible. Any number of railroad tracks on the railroad right-of-way could be connected to the same set of loud speakers 23 at the crossing 29, with the microphones connected in series as shown in Fig. 1.

In the said Fig. 1, two tracks designated 27 and 28 are illustrated and trains designated 31 and 32 are shown approaching the railroad crossing 29 from opposite directions. Both trains would be invisible, due to trees 33 and a curve in the railroad tracks, to the motorists on crossing 29. However, due to my warning signal device the motorist would be warned in ample time to stop. The loud speaker 23 and amplifier 20 would be incased in weatherproof and insulated casings and the cables interconnecting amplifiers and microphones would be insulated and waterproof.

A most important advantage in connection with my audible railroad crossing warning signal, is the fact that the actual sound of an on-rushing railroad train transmitted through its wheels 26 to rail 15 and picked up by microphones 8 and loudspeakers 23, greatly amplified, is made audible at the railroad crossing to warn approaching pedestrians and vehicles before the oncoming train is visible, giving ample time for stopping and thus avoiding accidents.

The fact that it is the actual sound of the moving trains transmitted through the rail attached microphones and the loud speakers that is heard at the railroad crossing, makes for a particularly effective warning. No person would ignore the sound of an approaching train greatly amplified, whereas many people will ignore bell 35 warnings.

Although I have herein described rather succinctly the nature and use of my invention so that persons skilled in the art will have no difficulty apprising themselves of the teachings 40 thereof and, inasmuch as the disclosure is susceptible of various alterations, modifications, and improvements, I hereby reserve the right to all modifications, alterations, and improvements

falling within the scope and spirit of my invention, as well as any modifications that are embraced suggestively in the accompanying drawings, and any that may come within the purview of the foregoing description; my invention to be limited only by the appended claim.

Having thus disclosed and revealed my invention, what I claim as new and desire to secure by Letters Patent is:

An audible railroad warning signal comprising, in combination with railroad tracks and truck wheels riding thereupon; a multiple number of microphone assemblies secured to the web portion of the said railroad tracks in spaced relation to react directly to the vibrations thereof caused by the said truck wheels at a time when the said truck wheels are directly over any of the said microphone assemblies; a source of electrical energy; a phonetic amplifier connected electrically to the said source of electrical energy; a loud speaker electrically connected to the said phonetic amplifier; and an electrical wiring circuit connecting in parallel the said microphone assemblies to the said phonetic amplifier and to the said loud speaker.

SYDNEY W. MADDEN.
